UNITED STATES PATENT OFFICE.

WILLIAM P. CARR, OF NEVADA, OHIO.

FENCE-POST.

SPECIFICATION forming part of Letters Patent No. 608,753, dated August 9, 1898.

Application filed March 25, 1896. Serial No. 584,895. (No model.)

To all whom it may concern:

Be it known that I, WILLIAM P. CARR, a citizen of the United States, residing at Nevada, in the county of Wyandot and State of Ohio, have invented a new and useful Improvement in Fence-Posts, of which the following is a specification.

My invention has relation to sheet-metal fence-posts; and it consists in the novel construction and arrangement of its parts, as hereinafter described.

The object of the invention is to provide a fence-post made of sheet metal, the metal being of a desired length, breadth, and thickness, said dimensions being uniform throughout the post, the metal being bent, preferably, in a triangle or rectangle or rounded in a transverse section, thus imparting great rigidity to the post and at the same time making it susceptible of being made of thin metal. The post is provided with a number of notches adapted to receive the horizontal wires used in the fence and the perpendicular rod adapted to slide by the post and pass the wires, and thus secure the wires in the notches.

The further object of my invention is to provide suitable anchors and guides to keep the post from being lifted or moved by the frost or any other element and also to prevent the post from sinking or settling in marshy or boggy ground. The further object of providing the anchors is to prevent the post from being laterally displaced or slanted.

In providing the guide for the post the shapes of the post and of the perforation through the guide are of importance. The guide is adapted to be held by means of a suitable flange at the surface of the ground, and the said guide is provided with a perforation that fits loosely about the post, the perforation being substantially of the same shape as the transverse shape of the post, the said perforation being thus either rounded or angular, as will be hereinafter explained.

In the accompanying drawings, Figure 1 is a perspective view of the post, showing the wires forming the fence secured in the notches. Fig. 2 is a perspective view of the post, showing the notches empty. Fig. 3 is an elevation of the rod adapted to hold the wires in the notches of the post. Fig. 4 is a perspective view of the guide adapted to be located

at the surface of the ground. Fig. 5 is a perspective view of the anchor adapted to be secured to the lower end of the post. Fig. 6 is a transverse sectional view of the upper anchor.

The post is made of a strip of metal 1. Said strip is formed with two sides extending at an angle to each other, said sides merging into each other at the central longitudinal axis of the post. The post is provided with the notches 2 2. Said notches are adapted to receive the wires 3 3, which form the fence. The wires 3 3 are held in place in the notches 2 2 by the rod 4, which passes down perpendicularly behind the rear surface of the post and in front of the said wires. The notches 2 2 are located in the apex of the angle formed by the sides of the post, and the rod 4 is confined by the angle made by the sides of the strip 1. The stationary plate 5 is adapted to be secured to the lower end of the post. Said plate is provided with an angular perforation 6, said perforation being of the same shape as the transverse shape of the post. Said perforation is adapted to receive the post, and the plate is made fast to the post. Said plate extends out substantially at right angles to the post. When the post is in position, the plate 5 is buried in the ground, and thus the post is held or anchored at its lower end. At the surface of the ground the post is provided with a guide 7. Said guide 7 is provided in its top with an angular perforation 8, which is substantially of the same shape as the transverse shape of the post. Said perforation is adapted to receive the post. The perforation 8 is of sufficient size to allow of the post slipping longitudinally therein; but the guide 7 forms a lateral bearing for the post, and by means of the angular shape of the post and the angular shape of the perforation 8 when the post slips longitudinally in the perforation 8 the guide 7 is not apt to be pulled from the ground by friction with the post. The guide 7 is provided with the downwardly-extending flange 9. Said flange is adapted to extend down into the ground, as shown in Fig. 1, and thus the guide 7 is secured to the ground, the upper face of the said guide being substantially at the same level with the surface of the ground. The anchor 5 is placed below

the frost-line, and when the frost gets in the ground around the guide 7 the said frost expands the ground and causes the guide 7 to rise. Owing to the shape of the post and the 5 shape of the perforation 8 there is a minimum amount of friction between the guide 7 and the post, and thus in its ascent the guide 7 will have no tendency to lift the post. Thus the post will be retained in its proper position by the 10 anchor 5, which is below the frost-line. As the frost in the surface of the ground is melted the surface of the ground contracts and the guide 7, of its own weight, falls. There being a minimum amount of friction between the 15 post and the edge of the perforation 8 of the guide 7, there will be no tendency on the part of the post to retain the guide 7 or to prevent it from descending.

Should the post be placed in marshy ground, 20 the guide 9 is of sufficient size to offer a resistance to any lateral strain caused by the wires or incidental to any other cause. The larger the guide 7 the harder it will be to move the said guide laterally, and in marshy ground 25 the guide 7 should be larger than in solid ground. Thus the guide 7 imparts a certain amount of leverage to the post and prevents any slant or lateral displacement of the post.

Having described my invention, what I claim as new, and desire to secure by Letters 30 Patent, is—

A fence-post consisting of a strip of metal of uniform length, breadth and thickness, said strip having its two sides bent at an angle to each other, the apex of the angle extending 35 along the longitudinal axis of the post, an anchor having an angular perforation, said perforation receiving the post, said anchor being permanently fixed to the post at or near its lower end, said anchor having its upper 40 and lower surface plain and extending substantially at right angles to the post, a guide having an angular perforation, said perforation adapted to receive the post, said guide being loosely mounted on the post and being 45 located at or near the surface of the ground, said guide having a downwardly-extending annular flange, said flange surrounding the post, said anchor adapted to move perpendicularly independent of the post, said guide 50 forming a lateral bearing for the post.

WILLIAM P. CARR.
